CLAIM

The ornamental design for a router and switch bracket, as shown and described.

DESCRIPTION

FIG. 1 is a front perspective view of a router and switch bracket;

FIG. 2 is a front elevation view thereof;

FIG. 3 is a rear elevation view thereof;

FIG. 4 is a left side elevation view thereof, the right side elevation view being a mirror image thereof.

FIG. 5 is a top plan view thereof; and,

FIG. 6 is a bottom plan view thereof.

The broken lines shown in the drawings illustrate portions of the router and switch bracket that form no part of the claimed design.
